Primary Examiner — George D. Kirschbaum*Assistant Examiner* — Mary Claire Ramirez(74) *Attorney, Agent, or Firm* — Bay State IP, LLC(57) **CLAIM**

The ornamental design for a pet brace, as shown and described.

DESCRIPTION

FIG. 1 is a front perspective view of a pet brace showing my new design;

FIG. 2 is a front view thereof;

FIG. 3 is a back view thereof;

FIG. 4 is a top view thereof;

FIG. 5 is a bottom view thereof;

FIG. 6 is a left side view thereof; and,

FIG. 7 is a right side view thereof.

The broken lines in FIG. 1 showing a dog wearing the pet brace is environmental subject matter and forms no part of

(Continued)

the claimed design. All other broken lines shown in the drawings depict portions of the pet brace that form no part of the claimed design.

1 Claim, 7 Drawing Sheets
